FUEL INJECTION PUMP

Herbert C. Edwards, Massillon, Ohio, assignor to
The Timken Roller Bearing Company, Canton,
Ohio, a corporation of Ohio

Application October 8, 1937, Serial No. 167,972

17 Claims. (Cl. 103—41)

This application is a continuation in part of my copending application for patent for improvement in Fuel injection pump, Serial No. 145,001 filed May 27, 1937.

5 The invention relates principally to fuel injection pumps of the kind having a plurality of reciprocating plungers that are rotated in their respective cylinders to regulate the quantity of fuel delivered. It has for its principal objects to provide for the quick and easy insertion and removal of the individual pump assemblies as complete preassembled units; to provide for properly positioning the pump units in the pump housing; to insure proper enmeshment of the plunger rotating pinions and the operating rack therefor; to obtain a uniform distribution of the wear on the tappet engaging surfaces of the tappet cups; and to provide for simplicity of construction, reduced cost of manufacturing, reduction in weight and compactness of design.

In the accompanying drawings, which form part of this specification and wherein like symbols refer to like parts wherever they occur,

25 Fig. 1 is a plan view of a fuel injection pump embodying my invention,

Fig. 2 is a side vertical central longitudinal section through the lower portion of the pump,

30 Fig. 3 is a vertical cross-section through the upper portion of the pump on the line 3—3 in Fig. 1,

Fig. 4 is a vertical transverse section on the line 4—4 in Fig. 1,

35 Figs. 5, 6, 7, 8 and 9 are fragmentary horizontal cross-sections on the line 5—5, 6—6, 7—7, 8—8, and 9—9, respectively, in Fig. 4.

Figs. 10 and 11 are fragmentary cross-sections similar to Fig. 6, showing how the removable pump unit clears the teeth of the rack bar when 40 the unit is inserted in and removed from the pump housing,

Fig. 12 is a side elevation of the driving sleeve of one of the pump units,

45 Fig. 13 is a bottom plan view of said driving sleeve,

Fig. 14 is a side elevation of the driven sleeve of one of the pump units,

Fig. 15 is a plan view of said sleeve,

40 Fig. 16 is a side elevation of one of the removable pump units,

Fig. 17 is a plan view of a portion of the pinion turning rack rod,

45 Fig. 18 is a fragmentary plan view of a modified pump construction,

Fig. 19 is a plan view of one of the plates for

angularly adjusting the pump units in the pump housing,

5 Fig. 20 is a vertical cross-section through the upper portion of said pump, the section being taken through one of the cylinders on the line 20—20 in Fig. 18; and

Figs. 21 and 22 are horizontal cross-sections on the line 21—21 and 22—22, respectively, of Fig. 20.

10 In the accompanying drawings, my invention is shown in connection with a fuel injection pump comprising a suitable housing 1 provided with a plurality of vertical bores 2 that are spaced apart lengthwise of said housing and lead downwardly through the top thereof into a longitudinal chamber 3 in the bottom thereof, within which is located a cam shaft 4 that is journaled in suitable bearings 4a in the end walls of said housing and is provided with lobe-shaped cams or tappets 5 adapted to engage tappet cups 6 slidably mounted in the lower portions of said vertical bores.

15 Located in each of the vertical bores 2 of the pump housing 1 is a pump assembly that is adapted and arranged for insertion in and removal from said bore as a complete preassembled and adjusted unit. Said pump unit or assembly

20 comprises a main supporting sleeve 7 having a cylindrical body portion 8, which is adapted to fit any one of the vertical bores 2 of the pump housing, and has oppositely extending ears or lugs 9 at its upper end that are perforated to receive the threaded upper ends of studs 10 that are threaded into said housing and are provided at

25 their upper ends with nuts 11 that bear against the upper surfaces of said ears or lugs and thus hold said supporting sleeve against both axial and rotary movement in the housing bore. The

30 supporting sleeve 7 has its lower end portion reduced to form an annular shoulder 12; and the housing bore is provided just below said shoulder with an annular seat adapted to receive a suitable

35 gasket 13. Said supporting sleeve is also provided just below the outstanding lugs or ears 9 at the upper end thereof with an annular groove 40

adapted to receive a gasket 14. The gaskets 13 and 14 serve to prevent leakage past the ends of the supporting sleeve.

35 Mounted in the supporting sleeve 7 of each pump unit is a pump cylinder or barrel 17 having an enlarged head or upper end portion 18 that is held down upon an annular seat 19 provided therefor in the lower end portion of the bore of said sleeve by means of a tubular member

40 20 having a base flange 21 that rests upon the

45

upper end of said cylinder. The cylinder 17 is prevented from rotating in its supporting sleeve 7 preferably by means of a pin 22 that is mounted in a radial hole in the wall of said supporting sleeve with its inner end seated in a recess provided therefor in the exterior surface of the head 18 of said cylinder. The bore of the tubular member 20 terminates at its upper end in a conical seat 23 for a suitable valve 24 that is held down on said seat by means of a coil compression spring 25. This valve seat member 20 projects into the lower end of the axial bore of a tubular shell or fitting 26; and the valve spring 25 is held under compression in said axial bore or passageway between a shoulder in said bore and a seat on the valve 24. A suitable washer or gasket 27 is interposed between the lower end of the fitting 26 and the base flange 21 of the valve seat member 20 for preventing leakage therebetween. This fitting is threaded into the upper end of the bore of the supporting sleeve 7 and has its upper end threaded for connection with a fuel line (not shown) that leads to a fuel injector (not shown). This spring holder or fitting serves to hold the valve seat member 20 down on the head 18 of the cylinder 17 and said head down on the annular seat 19 provided therefor in the bore of the supporting sleeve 7.

The head 18 of each pump cylinder 17 is provided on one side with a radial inlet port 28 and on the opposite side with a radial overflow, metering or by-pass port 29; and the cylinder supporting sleeve 7 is provided at about the level of said ports with a pair of spaced parallel bores 30 that pass through said sleeve transversely thereof on opposite sides of its axis and open into the bore thereof and communicate with the respective ports. The pump housing 1 is provided in its opposite ends at about the level of the passageways 30 in the cylinder supporting sleeves 7 with circular recesses 31, one of which is closed by a screw plug 32. The other of said recesses has a sleeve 33 threaded therein that is adapted to receive and support the threaded end of a fuel inlet pipe 33a. The pump housing 1 also has a pair of spaced parallel bores 34 therein that extend longitudinally of said housing from the plug receiving recess at one end thereof to the sleeve receiving recess at the opposite end thereof. These longitudinal bores are disposed on opposite sides of the axes of the vertical bores 2 of the pump housing, open into said bores and register with the bores 30 in the supporting sleeves 7 to form a passageway on one side of the cylinders that communicates with the inlet ports 28 thereof and a passageway on the other side of said cylinders that communicates with the overflow or by-pass ports 29 thereof.

Mounted for both rotary and axial sliding movement in the bore of the cylinder or barrel 17 of each pump unit is a plunger or piston 35 of the general type having an annular groove 36 therein that communicates through a longitudinal peripheral groove 37 with the pressure space above said plunger and has an inclined or helical upper edge 38, whereby said plunger may be turned in its cylinder to vary the point in its delivery stroke in which the overflow port 29 is placed in communication with said pressure space through the grooves 36 and 37. By this arrangement, delivery of the fuel begins as soon as the plunger on its way up covers the ports 28 and 29 and ends as soon as the helical upper edge 38 of the annular groove 36 in the plunger opens the

overflow or by-pass port 29 and thus relieves the pressure in the space above said plunger.

The mechanism for turning the plunger of each pump unit in its cylinder to vary the amount of fuel delivered thereby comprises a pinion 39 preferably formed integral with the upper end of a cylindrical driving sleeve 40 that is rotatably mounted on the cylinder 17 below the lower end of the supporting sleeve 7 therefor, and a driven sleeve 42 having a non-rotatable connection with said plunger below said driving sleeve. This non-rotatable connection comprises a flatsided portion 43 on the plunger that fits a similarly shaped opening 43a in the lower end of the driven sleeve 42. The driving connection between the driving sleeve 40 and the driven sleeve 42 comprises upwardly extending diametrically opposed tongues or tangs 44 on the driven sleeve that fit within downwardly opening diametrically opposed notches 45 located in the driving sleeve below a hub portion 41 thereof located just below the pinion 39 thereon, thereby permitting relative axial movement of the two sleeves, but preventing relative rotary movement thereof.

Surrounding the driving sleeve 40 and the driven sleeve 42 of each pump unit is a helical compression spring 46 that serves to retract the plunger. The tappet cup 6 surrounds the driven sleeve but is spaced far enough therefrom to accommodate the plunger retracting spring. Surrounding the upper portion of the driving sleeve 40 and the reduced lower portion of the main supporting sleeve 7 is a combination spring seat and driving sleeve support 48 comprising an annular spring seat 48a and an upward sleeve extension 48b whose upper end abuts against the annular shoulder 12 formed by said reduced lower portion of said main supporting sleeve. The length of the spacing sleeve or extension 48b of the member 48 is such that the driving sleeve 40 is supported on said spring seat portion 48a of said member with a slight clearance space between the upper end of said pinion 39 and the lower end of the main supporting sleeve 7.

The plunger 35 is provided below the lower end of the driven sleeve 42 with an annular groove 49 and terminates below said groove in a flat sided head portion 50. The lower end of the plunger retracting spring 46 is supported on an annular seat provided therefor on a member 51 having a lateral notch 52 therein, having a narrow upper portion that snugly receives the grooved portion 49 of the plunger and a wide lower portion that receives the head 50 at the lower end of said plunger. Thus, the spring seat member 51 is held against axial movement relative to the plunger but may rotate relative thereto and may be removed sidewise therefrom. The bottom wall of the driven sleeve 42 fits between the upper end of the spring seat member 51 thereon and a collar 35a formed integral with the plunger, thereby preventing relative axial movement of said sleeve and said plunger.

The spring seat 51 has a lower portion 53 of reduced diameter that bears against the bottom of the tappet cup 6, whose side walls are provided opposite said reduced portion with one or more oil drain and breather openings 54 through which access may be had to said spring seat for tappet inspection. Access to the openings 54 in the tappet cup 6 may be had through an opening 55, which is located in one side of the pump housing 1 adjacent to the lower end of said cup and is closed by means of a screw plug 56. The pump housing is also provided with a hollow

breather plug 57 provided with suitable filtering screens 58.

The tangs or fingers 44 of the driven sleeve 42 overlap the lower end portion of the cylinder 17 in all positions of the axial sliding movement of said sleeve and are provided with inwardly extending hooks or lugs 44a that fit within an annular groove 11a provided therefor in the peripheral surface of said cylinder. These hooks or lugs 44a are clear of the lower edge of the annular groove 11a in the operative position of the pump unit, but are adapted to bear against said edge of said groove when the pump unit is removed from the pump housing and thus retain the plunger retracting spring 46 under tension and prevent separation of the parts of the detached unit under the pressure of said spring.

As shown in the drawings, the pump is provided with a control rod 59 for simultaneously rotating the pinions 39 of all of the pump units. This rod is mounted for axial sliding movement in a longitudinal bore 60 provided therefor in the pump housing 1 and has one end extending beyond said pump housing for connection with a suitable mechanism (not shown) for reciprocating said rod, no fuel being delivered by the pump when said rod is at one end of its reciprocating movement and a maximum quantity of fuel being delivered when said rod is at the other end of said movement. Axial sliding movement of said rod is limited by a stop screw 59a that is threaded through the side of the pump housing and extends into a longitudinal groove 59b provided therefor in said rod. The rod is provided opposite each pinion 39 with a series of rack teeth 61 that intermesh with the teeth of said pinion. Near the "no delivery" end of each series of rack teeth 61 is a tooth space 62, the purpose of which will hereinafter appear, which is wide enough to receive two adjacent teeth of the pinion driven thereby.

Mounted on the hub 41 of the driving sleeve 40, just below the pinion 39 at the upper end thereof, is an indexing washer 63 whose opening is provided with a flat face 64 that cooperates with a similar face 65 on said hub and thus prevents relative rotary movement of said driving sleeve and said washer. The peripheral edge of the washer on the driving sleeve 40 is notched opposite the flat portion 64 of the opening therein to form a projecting tooth or lug 66 of a size and shape to pass only through the wide tooth space 62 in the series of rack teeth 61 that cooperate with the pinion 39 of said sleeve.

The combined spring seat and driving sleeve supporting member 48 is flattened, as at 48c, on its rack opposing side below the level of the pinion 39 to permit the lower end portion of said member to clear the rack teeth 61 when the unit is inserted in and removed from the bore in the pump housing. These flattened faces also insure positioning of the pump unit in one position only in the pump housing bore. The wall of the sleeve extension 48b of the member 48 is provided on its flattened rack opposing side 48c with an opening 48d so as to permit the pinion 39 to engage the rack teeth 61. The upper edge of this opening is provided with an inwardly extending tab or tongue 48e that fits into a notch provided therefor in the reduced lower end of the supporting sleeve 7 and thus prevents rotation of the spring seat when the driving sleeve 40 is rotated.

As shown in the drawings, the tappet cups 6 have convex spherical bottom surfaces 6a; and the cams or tappets 5 have conical surfaces 5a

that have tangential engagement with said tappet cups surfaces at points that are offset from the vertical axes of said cups, with the result that the cups are rotated during the operation of the pump, thereby distributing the wear evenly around the cam engaging surfaces of the cups. The cams 5 are all tapered in the same direction so that any effect of the tappet cup rotation on the metering action of the units will be the same on all units. 10

In the modified construction shown in Figs. 18 to 22, inclusive, the pump cylinder 17 is angularly adjusted in the supporting sleeve 1a by means of a screw plug 67 that is mounted in a threaded radial bore in said sleeve and has an eccentric pin 68 that extends into the overflow port 29 of said cylinder. Rotation of this plug causes the eccentric pin to turn about the axis of said plug and force the cylinder to rotate in its supporting sleeve and thus vary the position of the helical edge 38 of the annular groove 36 of the plunger 35 relative to the overflow port. In this construction, the entire pump assembly or unit is angularly adjusted in the vertical bore of the pump housing by means of a plate 69 that has a flatsided opening therein adapted to receive a similarly shaped flatsided portion on the upper end of the cylinder supporting sleeve 1a. This plate is secured flatwise to a removable top cover portion 1a of the pump housing by means of a nut 70 that is threaded on a stud 71, which is fixed to said housing and extends upwardly through said cover and through an arcuate slot 72 provided therefor in said plate. By this arrangement, the pump unit may be turned in the bore in the pump housing and then locked in the desired position of adjustment by tightening the nut 70. This nut bears against the upper surface of the plate 69. The cover plate 1a bears against an annular shoulder 7b provided therefor on the cylinder supporting sleeve 1a and thus serves to hold the pump assembly in the housing. 20 25 30 35 40

The hereinbefore described fuel injection pump has numerous advantages. It permits the entire pump assembly to be inserted in and withdrawn from the bore of the pump housing as a complete pre-assembled and accurately adjusted unit. The main supporting sleeve serves to rigidly hold the unit against both rotary and axial movement in the bore of the housing. The flatsided portion 50 of the combined spring seat and driving sleeve support 48 makes it impossible to insert the unit in the pump housing bore in any position except the correct position. The tooth 66 on the indexing washer 63 fits only the wide tooth space 62 of the rack, whereby the pinion 39 cannot be meshed with said rack except when said tooth passes through said wide tooth space, thereby insuring proper enmeshment of said pinion and said rack. The off-center engagement between 60 the conical surfaces of the cams and the spherical bottom surfaces of the tappet cups serve to impart a spinning movement to said cups and thus prevents the wearing of flat spots on said tappet cup surfaces. The tapering of all of the cams 65 in the same direction causes all of the tappet cups to rotate in the same direction and thus renders any effect that such rotation may have on the fuel delivery of the respective units, the same for each unit. Each pump unit assembly 70 may be quickly and easily detached for inspection or repair merely by removing the nuts that clamp the supporting sleeve to the top of the pump housing and withdrawing said unit from the bore thereof, leaving the tappet cup only in 75

said bore. The tappet cup may be withdrawn from the housing bore by removing the rack rod stop screw and withdrawing the rack rod.

What I claim is:

- 5 1. A pump assembly adapted for attachment to and detachment from a pump housing as a complete preassembled unit, said assembly comprising a supporting sleeve, a cylinder supported therein and extending therebelow, a plunger reciprocable in said cylinder and means for rotating said plunger in said cylinder, said means comprising a driving sleeve journaled on said cylinder below said supporting sleeve and having an axially slid able but nonrotatable connection with said plunger, a plunger retracting spring surrounding said driving sleeve, a seat on said plunger for the lower end of said spring, means for preventing endwise separation of said cylinder and plunger under the action of said plunger retracting spring, and a member surrounding said driving sleeve between said supporting sleeve and said spring and constituting a support for said driving sleeve and a seat for the upper end of said spring, the upper end of said member being held by said spring in abutting relation with the lower end of said supporting sleeve, whereby said driving sleeve is relieved of the pressure of said spring, said member and said driving sleeve being otherwise free from connections that would prevent endwise separation thereof.

10 2. A pump assembly adapted for attachment to and detachment from a pump housing as a complete preassembled unit, said assembly comprising a supporting sleeve, a cylinder supported therein and extending therebelow, a plunger reciprocable in said cylinder and means for rotating said plunger in said cylinder, said means comprising a driving sleeve journaled on said cylinder below said supporting sleeve, a driven sleeve fixed to said plunger, and having an axial slid able but nonrotatable connection with said driving sleeve, said driving sleeve having a pinion rigid with the upper end thereof, a plunger retracting spring surrounding said sleeve below said pinion, a seat on said plunger for the lower end of said spring, means for preventing endwise separation of said cylinder and plunger under the action of said plunger retracting spring, means on said driven sleeve cooperating with means on said cylinder for preventing endwise separation thereof under the action of said spring, and a member seated on the upper end of said spring and constituting a support for said driving sleeve and a seat for the upper end of said spring, said member being held by said spring against the lower end of said supporting sleeve, thereby preventing the pinion end of said driving sleeve from being forced against the lower end of said supporting sleeve by the pressure of said spring, said member and said driving sleeve being otherwise free from connections that would prevent endwise separation thereof.

15 3. A pump assembly adapted for attachment to and detachment from a pump housing as a complete preassembled unit, said assembly comprising a supporting sleeve, a cylinder supported therein and extending therebelow, a plunger reciprocable in said cylinder and means for rotating said plunger in said cylinder, said means comprising a driving sleeve journaled on said cylinder below said supporting sleeve and having an axial slid able but nonrotatable connection with said plunger, said driving sleeve having a pinion formed on the upper end thereof, a

plunger retracting spring surrounding said sleeve below said pinion, and a cylindrical spacing sleeve surrounding the pinion portion of said driving sleeve and constituting a support for said driving sleeve and a seat for said spring, said spacing sleeve being held by said spring in abutting relation to the lower end of said supporting sleeve, thereby relieving said driving sleeve of the upward thrust of said spring, said spacing sleeve having a non-rotary connection with said supporting sleeve comprising a tab extending inwardly from the upper edge of said opening and seating in a notch provided therefor in the lower end of said supporting sleeve, said spacing sleeve being provided on one side opposite said pinion with an opening adapted to permit engagement of said pinion with an operating rack therefor.

4. A pump assembly adapted for attachment to and detachment from a pump housing as a complete preassembled unit, said assembly comprising a supporting sleeve, a cylinder supported therein and extending therebelow, a plunger reciprocable in said cylinder and means for rotating said plunger in said cylinder, said means comprising a driving sleeve journaled on said cylinder below said supporting sleeve and having a pinion thereon and an axial slidable but non-rotatable connection with said plunger, a plunger retracting spring surrounding said sleeve, a seat on said plunger for the lower end of said spring, means for preventing endwise separation of said cylinder and plunger under the action of said plunger retracting spring, and a cylindrical spacing sleeve surrounding said pinion and a portion of the driving sleeve located therebelow and constituting a support for said driving sleeve and a seat for the upper end of said spring, the upper end of said spacing sleeve being held by said spring in abutting relation to the lower end of said supporting sleeve, said spacing sleeve and said driving sleeve being otherwise free from connections that would prevent endwise separation thereof, the side wall of said spacing sleeve being provided on one side opposite said pinion with an opening that terminates short of the upper and lower ends of said spacing sleeve and is adapted to permit engagement of said pinion with an operating rack therefor, the surface of said spacing sleeve below said opening being flattened to permit said surface to clear said operating rack when said pump assembly is inserted in and removed from said pump housing.

5. A pump assembly adapted for attachment to and detachment from a pump housing as a complete preassembled unit, said assembly comprising a supporting sleeve, a cylinder supported thereon and extending therebelow, a plunger reciprocable in said cylinder and means for rotating said plunger in said cylinder, said means comprising a driving sleeve journaled on said cylinder below said supporting sleeve and having a pinion thereon and an axial slidable but nonrotatable connection with said plunger, a plunger retracting spring surrounding said sleeve, and a spacing sleeve interposed between said spring and said supporting sleeve and surrounding the upper portion of said spring and constituting a support for said driving sleeve and a seat for said spring, said spacing sleeve being provided on one side opposite said pinion with an opening adapted to permit engagement of said pinion with an operating rack therefor, the surface of said spacing sleeve below said opening being flattened to permit said surface to clear said operating rack when said pump assembly

is inserted in and removed from said pump housing, the upper edge of said opening being provided with a lug adapted to engage a recess provided therefor in the lower end of said supporting sleeve, thereby preventing relative rotary movement of said supporting sleeve and said spacing sleeve but permitting endwise separation thereof.

6. A pump assembly adapted for attachment to and detachment from a pump housing as a complete preassembled unit, said assembly comprising a cylinder, a plunger reciprocable in said cylinder, means for rotating said plunger in said cylinder, said means including a pinion rotatable about the axis of said plunger and having an axial slideable but nonrotatable connection therewith and teeth all of equal width with unobstructed spaces therebetween, and a member located below and rotatable with but removable endwise from said pinion and having a projecting tooth located below two adjacent teeth of said pinion and of a width corresponding substantially to the combined width of said adjacent teeth and the space therebetween, as and for the purpose described.

7. A pump assembly adapted for attachment to and detachment from a pump housing as a complete preassembled unit, said assembly comprising a cylinder, a plunger reciprocable in said cylinder, means for rotating said plunger in said cylinder, said means comprising a pinion journaled on said cylinder and having a continuous series of equally spaced teeth all of equal width and an axial slideable but nonrotatable connection with said plunger, a nonrotatable member surrounding said pinion and having an opening therein on one side adapted to permit engagement of said pinion with an operating rack therefor, and a washer located in said member and located below and rotatable with but removable endwise from said pinion, said washer having a tooth projecting from the edge thereof, in line with and of a width corresponding substantially to the combined width of two adjacent teeth of said pinion and the space therebetween, as and for the purpose described.

8. A fuel injection pump comprising a housing having a bore therein, a supporting sleeve insertable in and removable endwise from said bore, a cylinder mounted in said supporting sleeve and extending therebelow, a plunger in said cylinder and means for rotating said plunger in said cylinder, said means including a pinion journaled on said cylinder and having teeth all of equal width and all with unobstructed spaces therebetween and a rack slideable in said housing and intermeshing with said pinion, one of the spaces between the teeth of said rack being relatively wide, and a separate member located below and rotatable with said pinion and having a single projecting tooth of a size to fit only the wide tooth space of said rack, whereby said pinion is prevented from being meshed with said rack except when said tooth passes through the wide tooth space of said rack.

9. A fuel injection pump comprising a housing having a bore therein, a supporting sleeve mounted in said bore, a cylinder mounted in said supporting sleeve and extending inwardly thereof, a plunger in said cylinder and means for rotating said plunger in said cylinder, said means including a pinion journaled on said cylinder and having a continuous series of equally spaced teeth all with unobstructed spaces therebetween and a rack intermeshing with said pinion, and

a separate member located inwardly of and rotatable with said pinion and adapted to permit enmeshment of said pinion with said rack in only one angular position of said pinion.

10. A fuel injection pump comprising a housing having a bore therein and a pump unit adapted to be inserted in and removed from said bore through the outer end thereof, said unit comprising a sleeve, a cylinder supported thereon and extending beyond the inner end thereof, a plunger reciprocable in said cylinder, and means for rotating said plunger in said cylinder, said means comprising a pinion journaled on said cylinder inwardly of said sleeve and having an axial slideable but nonrotatable connection with said plunger, a rack mounted in said housing and intermeshing with said pinion and having a continuous series of equally spaced teeth all of equal width and a wide tooth space adapted to receive two adjacent teeth of said pinion, and a washer rotatable with and located inwardly of said pinion and having a projecting tooth disposed in line with said two adjacent pinion teeth and of a size to fit only the wide tooth space of said rack, whereby said pinion is prevented from being engaged with said rack except when said tooth passes through the wide tooth space thereof.

11. A fuel injection pump comprising a housing having a vertical bore therein and a pump unit adapted for insertion in and removal from said bore through the outer end thereof, said unit comprising a supporting sleeve fitting in said bore, a cylinder supported in said sleeve and extending therebelow, a plunger reciprocable in said cylinder and means for rotating said plunger in said cylinder, said means comprising a driving sleeve journaled on said cylinder below said supporting sleeve and having a pinion thereon with teeth all of equal width and an axial slideable but nonrotatable connection with said plunger, a rack mounted in said housing and intermeshing with said pinion and having a wide tooth space adapted to receive two adjacent teeth of said pinion, a plunger retracting spring surrounding said sleeve, a member surrounding said pinion and a portion of said driving sleeve located therebelow and constituting a support for said driving sleeve and a seat for said spring, the upper end of said end member being held by said spring in abutting relation to the lower end of said supporting sleeve, said member being provided on one side opposite said pinion with an opening adapted to permit engagement of said rack with said pinion, the surface of said member below said opening being disposed in substantially flush alignment with the bottoms of the teeth of said pinion, and a washer fixed to said driving sleeve below said pinion and having a projecting tooth of a size to fit only the wide tooth space of said rack, thereby permitting said unit to be inserted in and removed from said bore only by passing said tooth through said wide tooth space.

12. A fuel injection pump comprising a housing, a plurality of pump units reciprocable therein, each of said units including a rotary and axially movable tappet cup, a shaft journaled in said housing and having a plurality of edge cams thereon spaced apart longitudinally thereof and adapted to actuate the respective tappet cups, said tappet cups having convex spherical cam engaging surfaces and said cams having continuous conical tappet cup engaging surfaces at their peripheral edges that have continuous tangential engagement with the convexly spherical

surfaces of said tappet cups at points offset from and on the same side of the axes thereof, the conical tappet cup engaging surfaces of said cams all tapering in the same direction.

- 5 13. A fuel injection pump comprising a housing having a shouldered bore therein, a supporting sleeve fitting in said bore and supported therein on the shoulder thereof and having a reduced outer end portion projecting beyond the outer 10 end of said bore and forming a shoulder on said sleeve, a pump cylinder mounted in said supporting sleeve, a plunger in said cylinder, and means for angularly adjusting said sleeve in said bore comprising a plate having a nonrotatable 15 connection with the projecting portion of said sleeve and means for securing said plate to said housing in the desired angularly adjusted position of said sleeve, and a plate removably secured to said housing at the outer end of said bore and 20 cooperating with the shoulder formed by the reduced outer end portion of said sleeve for holding the latter down on the shoulder in said bore.

14. A pump assembly adapted for attachment to and detachment from a pump housing as a 25 complete preassembled unit, said assembly comprising a supporting sleeve, a cylinder mounted therein and extending therebelow, a plunger in said cylinder, and means for rotating said plunger in said cylinder, said means comprising 30 a driving sleeve journaled on said cylinder below said supporting sleeve and having a pinion thereon and an axial slidible but nonrotatable connection with said plunger, a plunger retracting spring surrounding said driving sleeve, means for preventing endwise separation of said plunger and cylinder, and an annular seat for the upper end of said spring sleeved on said driving sleeve and having an upper sleeve extension surrounding said pinion with its upper end abutting against a shoulder provided therefor on said supporting sleeve, said sleeve extension and said driving sleeve being otherwise free from connections that would prevent endwise separation thereof.

15. A pump assembly adapted for attachment to and detachment from a pump housing as a complete preassembled unit, said assembly comprising a supporting sleeve, a cylinder mounted therein and extending therebelow, a plunger in said cylinder, and means for rotating said plunger in said cylinder, said means comprising a driving sleeve journaled on said cylinder below said supporting sleeve and having a pinion thereon and an axial slidible but nonrotatable connection with said plunger, a plunger retracting spring surrounding said driving sleeve, a seat fixed to said plunger for the lower end of said spring, means for preventing axial disengagement of said cylinder and plunger under the ac-

tion of said spring, and an annular seat for the upper end of said spring sleeved on said driving sleeve and having an upper sleeve extension surrounding said pinion with its upper end abutting against a shoulder provided therefor on said supporting sleeve, said sleeve extension fitting around the lower portion of said supporting sleeve and having a nonrotatable but axially disengageable connection therewith.

16. A fuel injection pump comprising a housing 10 having a bore therein, a supporting sleeve mounted in said bore, a cylinder mounted in said supporting sleeve and extending therebelow, a plunger in said cylinder, and means for rotating said plunger in said cylinder, said means comprising a driving sleeve journaled on said cylinder below said supporting sleeve and having a pinion thereon, a driven sleeve fixed to the lower end of said plunger and overlapping the lower end of said cylinder and having an axial slidible 15 but nonrotatable connection with said driving sleeve, a plunger retracting spring surrounding said driving sleeve, a seat on said plunger for the lower end of said spring, means on said driven sleeve cooperating with means on the portion of the cylinder overlapped thereby for preventing endwise separation of said plunger and cylinder, and an annular seat for the upper end of said spring sleeved on said driving sleeve and having an upper sleeve extension surrounding said pinion with its upper end abutting against a shoulder provided therefor on said supporting sleeve, said upper sleeve extension and said supporting sleeve being otherwise free from connections that would prevent endwise separation thereof.

17. A fuel injection pump comprising a housing having a bore therein, a supporting sleeve mounted in said bore, a cylinder mounted in said supporting sleeve and extending therebelow, a plunger in said cylinder, and means for rotating said plunger in said cylinder, said means comprising a driving sleeve journaled on said cylinder below said supporting sleeve and having a pinion thereon and an axial slidible but nonrotatable connection with said plunger, a plunger retracting spring surrounding said driving sleeve, and an annular seat for the upper end of said spring sleeved on said driving sleeve and having an upper sleeve extension surrounding said pinion with its upper end abutting against a shoulder provided therefor on said supporting sleeve, said sleeve extension fitting around the lower portion of said supporting sleeve and having a nonrotatable but axially disengageable connection therewith comprising a projection on said sleeve extension seating in a notch in the lower end of said supporting sleeve.

HERBERT C. EDWARDS.

CERTIFICATE OF CORRECTION.

Patent No. 2,185,146.

December 26, 1939.

HERBERT C. EDWARDS.

It is hereby certified that error appears in the printed specification of the above numbered patent requiring correction as follows: Page 4, second column, lines 9 to 14 inclusive, claim 3, strike out the comma and words ", said spacing sleeve having a non-rotary connection with said supporting sleeve comprising a tab extending inwardly from the upper edge of said opening and seating in a notch provided therefor in the lower end of said supporting sleeve" and insert the same after "therefor" and before the period, line 17, same claim; page 5, second column, lines 18 and 19, claim 10, strike out "a continuous series of equally spaced teeth all of equal width and" and insert the same before "an" in line 15, same claim; and that the said Letters Patent should be read with this correction therein that the same may conform to the record of the case in the Patent Office.

Signed and sealed this 12th day of March, A. D. 1940.
